ARTHUR R. GROTHE

BY *Henry H. Lloyd*
ATTORNEY

UNITED STATES PATENT OFFICE.

ARTHUR A. GROTHE, OF CHICAGO, ILLINOIS.

VACUUM-TUBE-EVACUATING APPARATUS.

Application filed April 22, 1925. Serial No. 25,033.

The present invention relates to a device for determining the state of vacuum in X-ray and other tubes, and has to do with an electrical circuit associated with tube baking 5 ovens and pumping apparatus to prevent damage to the tube during exhaustion.

Included in the objects of the invention are the following:

Means for periodically supplying energy 10 to a tube in the process of evacuation and means for automatically shutting off such energy if its employment is dangerous to the tube;

Means for supplying intermittently a pre- 15 determined amount of energy to a tube under process of exhaustion combined with self-actuated apparatus for shortening the period of application of such energy when dangerous to the tube structure;

20 A novel apparatus for supplying energy to a tube in predetermined periods in combination with automatic means for shortening such periods when damage to the tube may result, the apparatus being adapted to 25 adjust itself to a plurality of ranges of energies as the completeness of the exhaustion of the tube increases; and

30 A novel combination of automatic shut off means to be used in conjunction with a time switch.

These and such other objects as may hereinafter appear are obtained by the novel combination, arrangement, and construction of the several elements which constitute the 35 invention, one embodiment of which is disclosed in the accompanying drawing, comprising a schematic representation of such embodiment.

Like reference characters are used to 40 designate similar parts in the drawings and in the description which follows.

One form of the invention is disclosed. This form may be termed as "semi-automatic" to distinguish it from another form 45 which may be said to be "automatic" in its operation, which latter form is the subject matter of separate application for patent.

Both forms of the present invention relate to the evacuation of glass or other envelopes in which is disposed an electrode or electrodes, and while the description following relates to the exhaustion of X-ray tubes of the hot cathode type, this is but one of the many articles of current manufacture 55 to which the apparatus may be successfully

applied. It may be employed for the evacuation of gas X-ray tubes or other types of vacuum tubes by simple mechanical adjustment of the various control devices.

In the radiator type of X-ray tube, the 60 anode has a relatively large stem through which heat is dissipated with great rapidity. As previously stated, the cathode is of the "hot" or "heated" type. As is well known in the art, the amperage of high tension currents which may pass between electrodes in a completely evacuated X-ray tube depends wholly upon the temperature of the cathode therein.

In Figure 1 representative of the wiring 70 diagram of the semi-automatic apparatus, the numeral 1 is used to designate an X-ray tube having an anode 2 and a cathode 3. Through cathode 3, mains 4 and 5 feed the filament a low tension current from the secondary of a step-down transformer 6. The primary terminals of said transformer 6 are connected to the mains marked "Filament line," and the source of electromotive force in connection therewith (but not shown) is 75 a means for generating a current of constant voltage, such as a storage battery or a generator adapted to deliver a constant electric pressure.

In one of said filament line mains is a 80 current regulator 7 through which the flow of current through cathode 3 may be adjusted, thereby regulating the temperature of said electrode. In evacuating a radiator type of tube such as is illustrated at 1, it is 85 customary to employ successively three high tension currents of approximately 60 k. v. peak, the first employed being of two milliamperes, the second of five milliamperes and the third of ten milliamperes. The regulator 7 is therefore arranged to permit of 90 adjustments allowing the amperages indicated to pass between electrodes 2 and 3, and also to hold any adjustment made until manually advanced to the next higher adjustment.

From the mains 8 and 9, designated in the wiring diagram above referred to, as the "A-C line", the electromotive force required for operating and controlling the remainder of the apparatus is taken.

A conduit 10 extends from one of said mains 8, to a relay having contact points 11 and 12, one movable and the other fixed. From contact 12, a conduit 13 extends to a 110

control switch 14 which control switch includes a movable connector 15 adapted to engage, one at a time, contact points 16, 17 and 18. As will be noted in the drawing, the contacts 16, 17 and 18 are of three different heights and the reason for this will later be apparent.

From contact points 16, 17 and 18 conduits 19, 20 and 21, respectively, are connected to a resistance 22. When the movable connector member 15 engages contact 16 current passing through said member and contact will be required to pass through the whole of resistance 22; when movable contact 15 engages contact 17, the current will flow through less of resistance 22, and when said movable contact 15 engages contact 18 current will flow unhampered through resistance 22 except for a small amount of fixed resistance always in the circuit. From resistance 22, a conduit 23 runs to one terminal of the primary of a step-up transformer 24. A conduit 25 connects the other terminal of transformer 24 to main 9 whereby a circuit between mains 8 and 9 and including resistance 22 and transformer 24 is closed when contacts 11 and 12 are in engagement and the movable connector 15 impinges one of the contacts 16, 17 or 18.

From one of the terminals of the secondary of transformer 24, a main 26 runs to the anode 2 of tube 1. A conduit 27 from the other terminal of the secondary of transformer 24 is connected to one terminal of a pair of series connected magnets 28, the other terminal of said paired magnets 28 being connected by a conduit 29 to main 4 of the filament circuit between the step-down transformer 6 and the cathode 3. Such last mentioned connection is common in the art of connecting X-ray tubes of the hot cathode type for use in photography, etc.

Conduit 27 of the high tension circuit is connected to main 23 of the low tension circuit, and said main 23 is grounded at 23^a, as indicated.

The magnets 28 are disposed upon a reciprocating stand 30 adapted to be moved up or down by a standard 31 connected thereto and manually actuated by movements of connector member 15. The standard 31 and rotatable disc switch 14 are so associated that when switch 14 is rotated in a fixed horizontal plane the connector 15 thereon engages one at a time one of the contacts, 16, 17, or 18, and as said contacts 16, 17, and 18 are each of a different height, the standard 31 and its appended magnets 28 are moved toward or away from armature 41, rotation of switch 14 thus determining the relative position of magnets 28 and said armature 41.

From contact point 11, a conduit 32 is connected to one terminal of the coil of a relay 33 actuating contact 11, and from the other terminal of said relay coil, a conduit 34 ex-

tends to a tiltable mercury contact 35. From said mercury contact 35, a conduit 36 extends to the A-C line main 9. Current will flow between A-C line mains 8 and 9 through conduit 10, conduit 32, relay coil 33, conduit 34, mercury contact 35, and conduit 36, when the mercury contact 35 is closed. When said circuit is closed as indicated, the contacts 11 and 12 will engage one another, and current will flow to the step-up transformer 24. The volume of such current will be regulated by the position of the movable contact member 15 of the control switch 14. Concurrently with such flow, there will be generated in the secondary of transformer 24 a high tension current which will pass between anode 2 and cathode 3 in tube 1, in accordance with the temperature of cathode 3.

In the exhaustion or evacuation of an X-ray tube and other vacuum tubes, the volume of the gas in the tube decreases as the pumping of the tube continues. With high potential current in anode 2 and cathode 3 in a partly evacuated tube, the gas within the tube, being rarefied, ionizes, establishing an electrical current flow generally of greater intensity than is safe. The electrical apparatus supplying electromotive force therefore must contain means for breaking the circuit of high potential through the tube 1 when high potential of greater magnitude than is safe is passing between electrodes 2 and 3 otherwise a puncture therein will certainly occur. In the present apparatus, a margin of safety of two milliamperes has been established, so that when the intensity of the high tension current is two or more milliamperes above the amount for which the device is set the circuit between mains 8 and 9 through transformer 24 will be broken.

In the present device, a conduit 37 extends from conduit 32 into one terminal of a solenoid 38. From the other terminal of said solenoid 38, a conduit 39 extends to a fixed contact 40 disposed just above the magnets 28. A spring actuated armature 41 is connected by a conduit 42 to the conduit 36. Upon each face of the armature 41 is a contact point, 43 and 44, and when the armature 41 is pulled down sufficiently far, contact 43 thereon engages the fixed contact 40, establishing an electrical circuit between main 8 and main 9, through the conduits 10, 32, and 37, solenoid 38, and conduits 39, 42, and 36.

The reason for raising and lowering magnets 28 is now apparent. The distance said magnets are removed from armature 41 is governed by the height of contacts 16, 17 and 18. As the magnets 28 are further removed from armature 41, the greater is the electromotive force passing through said magnets 28 required to pull armature 41 (contact 43) into engagement with contact 40. Each of the contacts 16, 17 and 18 is adjustable.

Through the center of solenoid 38 a slideable rod 45 is disposed, said rod 45 being provided with a rack 46 engaging a pinion 47. Said pinion 47 is of the ratchet type and is allowed to turn slowly and in a clockwise direction by a clock mechanism (not shown) connected therewith. The weight of rod 45 is the sole actuating force therefore. The ratchet associated with pinion 47 permits it to be rotated in a counterclockwise direction without interference with the movements of the clock mechanism.

By this arrangement rod 45 may be forced upwardly at any time, and is kept from immediately descending by the pinion 47 which will allow the rod 45 to move only at a predetermined rate of speed wholly controlled by the clock mechanism referred to. The instant contact is made between fixed contact 40 and armature 41 (contact 43), a circuit is established through the solenoid 38. This circuit causes the rod 45 to move upwardly. Ordinarily, the period of engagement between contacts 40 and 43 is very brief and the rod 45 would not rise the full length of its path of travel as a result of such brief make, hence, means are provided whereby another circuit is established through the solenoid 38 and continued a sufficient time to carry the rod 45 to the top extremity of its path of movement. This circuit will now be described.

At the lower end of rod 45 is a section 48 insulated from the main body of rod 45 by suitable insulation 49. Section 48 carries a conducting cross member 50 which is adapted to engage a pivoted contact member 51. Member 51 comprises an arm having a top flange 52 partly of conducting material and partly a shoe 52^a of non-conducting material, and a bottom flange 53 of non-conducting material.

The space between flanges 52 and 53 is comparatively small and it is into this space that one end of the member 50 projects. The slight impact given to rod 48 by "make" between contacts 40 and 43 lifts the rod 45 sufficiently that the cross member 50 is raised from engagement with non-conducting flange 53 to engagement with the conducting flange 52. A circuit is thus established through conduits 10, 32 and 37, solenoid 38, conduits 39, tiltable member 51, cross member 50, rod 48 and a conduit 54 having a flexible connection with and extending from rod 48 to main 36. In practice, it is customary to connect main 39 to tiltable member 51 by a brush connection or sliding contact. Such a connection is desirable in that it retards free movement of member 51 and makes it necessary to actuate said member by an external force before it may be displaced in any direction.

By the circuit just described, the movement of rod 45 to its topmost position is as-

sured. The momentum which said rod attains is quite great, and this momentum is utilized in breaking the circuit last referred to.

Upon the point of flange 52 is a shoe 52^a of a non-conductor, as hereinabove stated. The length of shoe 52^a is such that just before rod 45 reaches its topmost point, cross member 50 breaks contact with flange 52 and rests in engagement with non-conducting shoe 52^a. Disengagement between cross member 50 and flange 52 breaks the "lifting" circuit, and the momentum of rod 45 is useful in rendering certain that said cross member 50 will be drawn free from "making" contact with flange 52. As the brush or sliding contact upon arm 51 frictionally maintains said arm against dropping, the said arm 51 remains in its uppermost position until external forces cause it to travel downwardly.

Upon the rod 45 is a second cross member or arm 55 which in its upward movement is adapted to tilt the mercury contact 35, breaking the connection through the relay 33 and allowing contacts 11 and 12 to separate where-by electromotive force is shut off from transformer 24. The high tension current generated in the secondary of such transformer immediately ceases, and the tube 1 is saved from overheating or puncture.

When the rod 45 has reached its uppermost position, and the circuit through solenoid 38 is broken as has been described, the rod 45 of its own weight, will begin to descend at a predetermined speed controlled by the clock mechanism of which pinion 47 is a part. As rod 45 descends, the cross member or arm 55 releases the mercury contact 35, so that the relay circuit is re-established, causing contacts 11 and 12 to impinge and re-establish the passage of electromotive force through the transformer 24, with a concurrent production of high tension current passing through the tube 1. It takes a predetermined time for the rod 45 to travel from its uppermost position to its lowermost position. As it drops, rod 45 also impinges the flange 53 on arm 51, and forces it downwardly also.

If no gas is ionized in tube 1, auxiliary means are necessary in order to periodically break the circuit through transformer 24 for otherwise the tube 1 will become overheated. This auxiliary means for establishing a circuit through the solenoid 38 comprises a mercury contact 56 one end of which engages the conduit 57 flexibly connected to rod 48. As the rod 45 travels downwardly until it closely approaches its lowermost point of travel, arm 50 engages the mercury contact 56 and tilts it to establish a circuit from conduit 39 through contact 56, conduit 57, rod 48 and conduit 54. The connections in the circuit just described and the A-C line mains 8 and 9 recited in detail comprise the following: conduits 10, 32 and 37, solenoid 38, conduit 39, mercury con-

tact 56, conduit 57, rod 48, and conduits 54 and 36. This "make" gives to rod 45 an impulse causing cross member 50 to impinge flange 52, producing the "lifting" circuit for rod 45 previously described, whereby rod 45 is carried to its topmost position.

The timing of the movements of the several parts of the device is of importance. In view of the adjustability possessed by all of the parts, including the clock works, any desired length of "off" and "on" of high potential in tube 1 may be had. For radiator types of tubes, the heat of the tube is sufficiently dissipated to prevent overheating if the "off" and "on" periods, alternately occurring, are of fifteen seconds duration. The automatic features of the device shorten the "on" period if danger appears, but the "off" periods remain at fifteen seconds due to the clockworks referred to hereinabove.

A specially wound, constant voltage, A. C. generator, driven by a synchronous motor, is used to supply current to the filament line with excellent results. In the wiring diagrams it will be noted that the filament circuit is on the grounded side; hence, no provision for high voltage insulation between the primary and secondary of the filament transformer would be necessary were the device to be always used alone. But it is sometimes necessary to connect the tube 1 to a transformer delivering a voltage of about 130 k. v. (peak) in which event, an insulated filament winding is necessary. Having the filament circuit on the grounded side also simplifies the circuit.

Condensers 58 are connected in the circuit to prevent sparking between windings of the magnets 28 and the stand 30 and standard 31. If such condensers are not in circuit, the high frequency currents generated whenever gas appears in tube 1 will tend to jump to the stand 30 and standard 31 instead of going through the coils. Under such conditions, the armature 41 will not be attracted to the contact 40. The current will continue to flow in the tube 1, and if sufficient gas is generated, the tube 1 will be punctured. Said condensers 58 are connected in series in the high tension circuit and grounded at the center to standard 31. A condenser 59 is connected across armature 41 and contact 40 to reduce sparking.

A non-inductive resistance surge arrester 60 grounded at its center is connected across the winding of solenoid 38, to prevent the winding thereof from being punctured due to high frequency surges produced in the primary circuit. Similar arresters 61 and 62 are placed across the relay winding 33 and the primary winding of the transformer 24.

Should the current in tube 1 be deficient with respect to its intensity, a visual signal is provided. The deficiency to operate said signal is approximately two milliamperes or more.

Above contact 44 on armature 41 is a contact 63, connected to a conduit 64 connected to conduit 13 and in which a light 65 is disposed. If the intensity of the high tension current falls below the milliamperage required, contacts 44 and 63 make and current flows through light 65, the signal circuit being conduit 10, contacts 11 and 12, conduit 64, contacts 63 and 44, and conduit 42.

As previously indicated, armature 41 is spring actuated. The adjustment of the spring (not shown) is such that said armature contact 44 normally rests against contact 63. The passing of current of proper intensity through magnets 28 causes said magnets 28 to pull armature 41 into a neutral position intermediate contacts 40 and 63. The armature 28 remains in such neutral position so long as a proper current flows in the high tension circuit, but the contacts thereon, 43 and 44, will move into engagement with contacts 40 or 63, respectively, when an excess or an insufficiency of high tension current develops. Armature 41 is heavily weighted to reduce vibration, hence moves only under the influence of a positive force. This prevents vibrating "makes" between contacts 40 and 43 and contacts 44 and 63.

A manually actuated spring release switch 66 may be inserted between conduits 13 and 37 to provide for establishing high tension current irrespective of the position of the remainder of the apparatus.

I claim:—

1. A device associated with a vacuum tube during evacuation comprising means for periodically supplying a predetermined volume of energy thereto, means responding to an excess of energy in said tube for terminating such energy supply when its volume becomes excessive, and manually controlled means for increasing said volume of energy as evacuation of the tube progresses.

2. A device to be employed with a vacuum tube during evacuation comprising means for periodically supplying a predetermined volume of energy thereto, means responding to an excess of energy in said tube for terminating such energy supply when its volume has become excessive, and manually controlled means for increasing said volume of energy as evacuation of said tube progresses, and in which said energy supplying and terminating means comprises a time actuated relay.

3. The combination with a circuit for supplying energy to a vacuum tube during evacuation comprising a main line to a step-up transformer, a high tension line from said transformer to said tube, a time actuated relay automatically terminating the admission of energy to said tube, and manually controlled means for increasing the volume of energy admitted to said tube, of an armature movable in one direction to actuate said energy terminating means, and a signal

adapted to be actuated when said armature is moved in another direction.

4. The combination with a circuit for supplying energy to a vacuum tube during evacuation comprising a main line to a step-up transformer, a high tension line from said transformer to said tube, a time actuated relay automatically terminating the admission of energy to said tube, a signal for indicating increase in the vacuum in said tube, and manually controlled means for increasing the volume of energy admitted to said tube, of an armature adapted to be actuated by the energy flowing through said tube to control said means for terminating the flow of current to said tube.

5. In a tube evacuating apparatus, a low tension circuit to a transformer, a high tension circuit from said transformer, a magnet in said high tension circuit, a spring actuated armature disposed within the influence of said magnet, a relay adapted to be actuated by said armature when moved in one direction and opening said low tension circuit, and manually controlled means for separating said magnet and armature.

6. The apparatus described in claim 5, and in which relative movement of said magnet and armature regulate the volume of energy which may flow in said high tension circuit.

7. The apparatus described in claim 5, in combination with a visual signal adapted to be actuated by said armature when moved in the opposite direction.

35 8. For supplying electromotive force to a vessel in process of evacuation, a circuit comprising a relay, and contacts actuated by an armature for operating said relay, in combination with a magnet for actuating said armature, and means for manually determining the relative position of said magnet and said armature.

9. For supplying electromotive force to a vessel in process of evacuation, a circuit comprising a relay, and contacts actuated by an armature for operating said relay, in combination with a magnet for actuating said armature, and means for manually separating

ing said magnet and said armature a plurality of predetermined distances.

50

10. In combination, a low tension circuit to a transformer and having a resistance and a relay therein, a high tension circuit from said transformer to a tube in process of evacuation, a magnet in said high tension circuit, a base for said magnet and adjustably mounted, an armature in juxtaposition to said magnet and adapted to close the circuit to said relay, and a switch member for eliminating resistance in said low tension circuit, actuation of said switch member being adapted to modify the relative position of said magnet base to said armature.

55

11. In combination, a low tension circuit to a transformer and having a resistance and a relay therein, a high tension circuit from said transformer to a tube in process of evacuation, a magnet in said high tension circuit, a base for said magnet and adjustably mounted, an armature in juxtaposition to said magnet and adapted to close the circuit to said relay, and a switch member for eliminating resistance in said low tension circuit, actuation of said switch member being adapted to modify the relative position of said base to 60 said armature, and in which said magnet base has a plurality of adjustments coinciding with the points upon said resistance switch.

65

12. In combination, a low tension circuit to a transformer and having a resistance and a relay therein, a high tension circuit from said transformer to a tube in process of evacuation, a magnet in said high tension circuit, a base for said magnet and adjustably mounted, an armature in juxtaposition to said magnet and adapted to close the circuit to said relay, and a switch member for eliminating resistance in said low tension circuit, actuation of said switch member being adapted to modify the relative position of said magnet base to said armature, said magnet base having a cam surface adapted to be engaged by said handle for adjusting the magnet on said base relatively to said armature.
